UNITED STATES PATENT OFFICE.

JOSEPH HALL, OF LEEDS, ENGLAND.

DESIGN FOR A FINISHING ROLL OR CYLINDER.

SPECIFICATION forming part of Design No. 29,343, dated September 13, 1898.

Application filed August 11, 1898. Serial No. 688,400. Term of patent 14 years.

To all whom it may concern:

Be it known that I, JOSEPH HALL, a subject of the Queen of Great Britain, residing at Leeds, in the county of York, England, have 5 invented and produced a new and original Design for Finishing-Rolls for Hides, Skin, and Leather Machinery, of which the following is a specification, reference being had to the accompanying drawings, forming part hereof, 10 in which—

Figure 1 is a front elevational view of a roll or cylinder showing my new design. Fig. 2 is a plan view of the periphery of the roll or cylinder projected upon a flat surface. 15 Fig. 3 is a transverse sectional view of Fig. 1 on the line $x-x$, and Fig. 4 is a diagram illustrating the angular arrangement of certain of the blades or vanes upon the periphery of the roll or cylinder. 20 As illustrated in the drawings, the leading feature of my design consists of the cylindrical body or base A of the roll or cylinder, from which projects a series of disconnected 25 blades or vanes a, arranged parallel to the longitudinal axis of the roll or cylinder, in connection with a series of oppositely-arranged disconnected helical main blades b and two or more series of short blades or vanes d and e, these short blades or vanes 30 d and e being also oppositely arranged in series and certain of these blades d or e approaching toward each other or converging at d' or e' near the center of the cylinder or

roll, but not abutting. The series of short blades d are arranged at an angle to the disconnected horizontally-arranged blades a and the disconnected helical blades b, and the short blades e are likewise arranged at an angle to the blades a and b, but the angles of the blades d and e vary. This angular arrangement of the blades b, d, and e is illustrated in Fig. 4. The projecting edge of each blade, whether of the series a, b, d, or e, is rounded, as at a², b², d², and e², and when the blades b, d, and e are arranged on the rounded 35 body A of the cylinder or roll, as illustrated in Fig. 1, they present a curved appearance. The rounding of the edges a² of the blades a gives to the cylinder a scalloped effect, which effect is heightened when the roll is turned 40 to the position illustrated in Fig. 1, when one series of blades a is arranged diametrically opposite to another series of the blades a. 45 Having thus described my invention, what I claim as new, and desire to secure by Letters 50 Patent, is—

The design for a finishing roll or cylinder, substantially as herein shown and described.

In testimony whereof I have hereunto set my signature in the presence of two subscribers. 60

JOSEPH HALL.
